UNITED STATES PATENT OFFICE.

WILLIAM F. REDDING, OF TANGERINE, FLORIDA.

CRATE FOR FRUIT, &c.

SPECIFICATION forming part of Letters Patent No. 330,620, dated November 17, 1885.

Application filed September 18, 1885. Serial No. 177,429. (No model.)

To all whom it may concern:

Be it known that I, WILLIAM F. REDDING, a citizen of the United States, residing at Tangerine, in the county of Orange and State of Florida, have invented a new and useful Improvement in Crates for Fruit and Vegetables, of which the following is a specification.

My invention relates to an improvement in crates for fruit or vegetables, providing for dividing the crate, so that half may be used or sold without breaking bulk of a whole crate; and it consists in providing for dividing the crate into two sections by sawing apart, and so that each portion will be left perfect in itself, substantially as hereinafter set forth, reference being had to the accompanying drawings, in which—

Figure 1 is a side elevation; Fig. 2, a cross-section through the center board, and Fig. 3 a detailed view.

In my construction I make a crate, A, in the ordinary manner with a center board or partition, B, dividing the crate into two parts. This board being of sufficient thickness to be divided in half surfacewise, I cut it away with a saw in the center from all the edges, and leave only a small portion, C—one-fourth,

more or less—not cut, (see Figs. 2 and 3,) and this board is nailed in position with separate nails D through the slats E into each portion of the board. Then, when it is desirable from any cause to sell or use only one-half of a crate, with a saw the slats E are cut in two over the saw-kerf F in the board B, and the uncut portion C is also sawed through, leaving two perfect half-size crates; and this is a great convenience to those using or selling crates, where only one-half is needed for a given time.

What I claim as my invention, and desire to secure by Letters Patent, is—

The crate A, provided with the partition-board B, having in it the saw-kerf F and the uncut portion C, and the slats E, nailed in the center to the two sections of the partition, so that the said slats may be cut in two between these two rows of nails D, and the portion C also be cut, dividing the crate into two perfect parts, substantially as and for the purpose specified.

WILLIAM F. REDDING.

In presence of—

G. A. TREMAIN,
R. C. TREMAIN.
